Specification of Letters Patent. Patented Apr. 30, 1918.

Application filed July 26, 1916. Serial No. 111,527.

To all whom it may concern:

Be it known that we, ARTHUR ERNEST JERRAM and JOSEPH GOULBOURN, subjects of the King of England, residing at Leicester, Leicestershire, England, have invented 5 certain Improvements in Fastening-Inserting Machines, of which the following description, in connection with the accompanying drawings, is a specification, like reference characters on the drawings indicating like parts in the several figures.

This invention relates to machines for inserting fastenings. By way of illustration the invention is herein shown as embodied in 15 a machine of the type disclosed in United States Letters Patent No. 490,621, granted January 24, 1893, on an application of Louis Goddu, for inserting screw threaded fastenings in the soles of boots and shoes.

20 In the use of machines of the general type disclosed in said Letters Patent on some classes of work, the maximum spacing desired exceeds considerably the maximum spacing obtainable with machines of this type as these machines have been constructed heretofore. Also, it is frequently desired to make considerable changes in the spacing of the fastenings at different parts of a given shoe. Consequently, in such cases, it

30 has been necessary for the operator to advance the work manually between successive fastening locations, depending necessarily upon his own skill and accuracy to effect the different spacings properly and to 35 locate the fastenings correctly, with the result not only that especial skill has been required on the part of the operator and the operator's work has been rendered considerably more laborious, but the output of the 40 machine has been reduced considerably and the results obtained have generally been unsatisfactory.

One of the objects of the present invention is to eliminate these disadvantages by producing 45 an improved fastening inserting machine especially adapted for inserting screw threaded fastenings in the soles of boots and shoes, which machine may readily be rendered capable of dealing either with any 50 ordinary and normal spacings or with spacings considerably outside of the normal range of spacings.

A further and more particular object of the invention is to provide an improved fas-

tening inserting machine of this general 55 type so constructed as to permit a change from normal to extra wide spacing to be made at the will of the operator without interrupting the operation of the machine to provide for effecting any desired changes 60 of spacing during the operation upon a given shoe without necessitating either stopping the machine or rendering necessary a second series of operations upon that shoe to insert the extra widely spaced fastenings 65 after the normally spaced fastenings have been inserted.

In accordance with these and other objects of the invention, the illustrated machine is 70 provided with novel manually controlled means capable of initiation by the operator at any stage in the operations of the machine, which means are so constructed and arranged that whenever extra wide spacings are desired the operation of the fastening 75 inserting mechanism may be suspended periodically without suspending or interfering with the operation of the work feeding mechanism, to the end that the amount of work feeding movement between successive 80 fastening inserting operations may be doubled, thereby doubling the spacing range of the machine.

Preferably, and as shown, the illustrated 85 means for periodically suspending the operation of the fastening inserting mechanism is organized to act automatically at regular intervals during the operation of the machine, the construction and arrangement being such that the initial suspension 90 of operation of the fastening inserting mechanism will invariably occur at a predetermined point in the cycle of operations of the machine regardless of when the operator actuates the means for suspending the 95 operation of this mechanism. As herein shown, this result is accomplished by automatically suspending the operation of the fastening inserting mechanism at a predetermined time between each two fastening 100 inserting operations, so that, as long as extra wide spacing is desired, the work feeding mechanism will impart to the work two work feeding steps between every two successive fastening inserting operations.

105 These and other objects and features of the present invention will be apparent from the following detailed description of a ma-

chine of the above mentioned type having a preferred embodiment of the present invention incorporated therein, and the novel features of the invention are defined in the 5 appended claims.

Referring to the drawings,

Figure 1 is a side elevation of the upper portion of the machine; and

Fig. 2 is a front elevation, partly in section, showing certain parts of the upper portion of the machine of Fig. 1 on a somewhat larger scale.

The machine in which the present invention is herein shown as incorporated is substantially the same as that disclosed in said above mentioned Letters Patent except as hereinafter set forth, and reference may be had to said Letters Patent for a more detailed description of the construction and 20 operation of certain parts not fully described herein.

The machine has a base carrying a column 2 which supports a head 4 having mounted therein a vertically disposed spindle 6 which 25 carries the screw threaded wire from which the fastenings are formed. The spindle 6 is continuously rotated by a belt passing over a pulley 8 on the upper end of the spindle and over idlers 10 to a driving pulley (not 30 shown) in the base of the machine arranged to be clutched to a continuously running pulley operated from a source of power. The spindle 6 is provided with a worm which engages worm gears 20 (Fig. 1) upon the 35 forward ends of parallel shafts, one of which is indicated at 22, this shaft 22 carrying the various cams for effecting the wire feeding, wire severing, work feeding, and automatic horn depressing movements. 40 These cams are each formed to cause two operations of the parts operated thereby during each complete revolution of the cam shaft 22.

The wire is fed downwardly through the 45 spindle 6 by a wire feeding and inserting sleeve 24 surrounding the spindle 6 and slidably mounted in guideways in the machine frame, the lower end of said sleeve being provided with wire gripping members 50 26 which operate intermittently to seize the wire as said sleeve is moved downwardly. The sleeve 24 is reciprocated in the machine frame to feed successive lengths of wire and insert them in the work by a wire feed 55 lever 28 (Fig. 2) pivoted at 30 to the machine frame and having two forwardly projecting arms 31 (Figs. 1 and 2) each carrying a segmental gear 32, the gears 32 engaging respectively racks 34 formed on a yoke 60 attached to the upper end of the sleeve 24. An upwardly extending arm 36 (Fig. 2) of the lever 28 carries a cam roll 38 operatively engaged by a wire feeding edge cam 40 on the cam shaft 22. A wire feed lever 28 is 65 normally held in position to be operated by

the cam 40 to move the wire feeding sleeve 24 downwardly by a comparatively strong spring (not shown) the lower part of which bears against a part of the lever 28.

After a proper length of wire has been inserted in the work, the wire is severed by wire severing knives mounted in the lower ends of two knife carrying arms 41 and 43 both fulcrumed on a shaft 47 mounted in the machine frame. The knife carrying arms or 70 holders 41 and 43 carry gears (not shown) which mesh with coöperating gears on the forward end of a shaft 51 (Fig. 1). Upon 75 rocking movement of the shaft 51, the holders 41 and 43 are reciprocated toward and from each other to cause the cutting edges of the knives to sever successive lengths of wire in timed relation to the operation of the wire feeding mechanism. The shaft 51 is oscillated through connections to a wire severing cam 45 provided with two outstanding toes one of which is shown at 53 and adapted to operate intermittently a lever 49 operatively connected to the shaft 51.

In the use of the machine the shoe to be 90 operated upon is mounted upon a horn (not shown) and clamped between the horn and an abutment indicated at 55. In order that each wire fastening inserted in the work may correspond to the thickness of the work at 95 the fastening location, the extent of feeding movement imparted to the wire feed lever 28 by the wire feeding cam 40 is automatically varied. This is effected by providing the horn with a laterally extending arm (not 100 shown) to the outer end of which is attached a measuring rod or leg 59 (Fig. 2) projecting upwardly through a guide in the machine frame and adapted upon upward movement of said rod to engage and move 105 upwardly a coöperating rod 61, the lower end of which is in line with, but normally spaced from, the upper end of the rod 59. The rod 61 has its upper end pivotally secured to the end of a rearwardly extending 110 arm 63 of the wire feed lever 28. Whenever the horn is moved upwardly into work clamping position, the measuring rod 59 is correspondingly moved to engage and move the coöperating rod 61, whereupon the wire 115 feed lever 28 is adjusted in respect to its operating cam 40 according to the thickness of the work.

After each fastening has been inserted and cut off, the work is automatically fed 120 by a feed wheel 127 (Fig. 1). The feed wheel 127 carries on its under side a bevel gear indicated at 123 meshing with a bevel gear 125 on the outer end of a shaft 129. The opposite end of the shaft 129 carries 125 loosely a toothed sleeve 131 adapted to be oscillated by a rack 139 (Fig. 2) on the lower end of one arm of a two-armed lever 133. The other arm 141 of this lever has a stud and slot adjustable connection indi- 130

cated at 143 with a lever 145, the upper end of which lever carries a cam roll 147 traveling in a cam track in the wire feed cam 40. A pawl 135 on the sleeve 131 engages a ratchet 137 on the shaft 129 and operates to rotate shaft 129 when the sleeve 131 is oscillated. Means (not shown) are provided to prevent backward or reverse rotation of the feed wheel 127 when the lever 133 is being returned to normal position under the influence of a spring pressed plunger (not shown).

The above described mechanisms and parts conveniently may be, and as shown are, constructed and operate substantially as described in the above mentioned Letters Patent No. 490,621.

To permit the work to be fed between successive fastening inserting operations, the horn is periodically depressed through automatic horn depressing mechanism (not shown) which may be of any suitable construction such, for example, as that fully set forth in United States Letters Patent No. 383,455, granted May 28, 1888, on an application of Louis Goddu.

As above stated, the wire carrying spindle 6 is rotated continuously. To provide for starting and stopping the operation of the wire feeding mechanism and for simultaneously controlling the operation of the wire cutting mechanism, as well as for locking the horn in its lowered position when it is not desired to insert fastenings, the illustrated machine is provided with a control mechanism of the type illustrated and described in United States Letters Patent No. 691,354, granted January 21, 1912, on an application of Louis A. Casgrain, and the illustrated embodiment of the present invention is especially designed and adapted for use in connection with a control mechanism of this general type.

The illustrated control mechanism comprises a treadle (not shown) connected by a treadle rod 50 (Fig. 2) to a lever 52 pivoted on the machine frame and carrying an upstanding spring blade 54 which engages a latch 56 carried by a lever (not shown) having a cam roll traveling in a cam track on the rear side of the cam 40 whereby the said lever and the latch 56 are continuously reciprocated. The latch 56 is provided with ears or lugs adapted upon upward movement of the said latch to engage corresponding ears or lugs on a switch member 58, fulcrumed on the machine frame, to set the switch member 58 in position to stop the operation of the wire feeding and cutting mechanisms and to maintain these mechanisms inoperative.

Upon movement of the treadle one way or the other, the latch 56 is swung correspondingly through the lever 52 and spring blade 54, depression of the treadle moving

the lever 52 in a direction to allow the latch 56 to turn the switch member into position to restore operative connection between the wire feeding and cutting mechanisms and their operating cams, and return movement of the treadle to its normally raised position operating reversely through the lever 52 and spring blade 54 to force the switch member into position to stop the operation of these mechanisms.

For controlling the operation of the wire feeding mechanism, the switch member 58 is connected by a lever 159 with a stop 60 adapted, upon movement of the lever 159 to the right, to be positioned under a shoulder 63 on the rod 61, the stop 60 having an inclined wedge-shaped face which, when the said stop is moved into its operative position, acts positively to force the rod 61 upwardly and then to move the wire feed lever 28 a distance greater than the amount of movement imparted to the lever 28 by its cam 40, thus moving the cam roll 38 on the upper arm 36 of the lever 28 out of contact with the cam 40 and rendering the wire feeding mechanism inoperative.

The switch member 58 has connections, not herein shown but fully described in United States Letters Patent No. 691,354, with the knife operating lever 49, these connections comprising a slot in the upper end of one arm of the switch member 58 in which is received a lug carried by the link or lever through which the toes 53 on the knife operating cam 45 operate, the lever 49 operating to swing said other lever out of the path of movement of the toes 53.

As above stated, the stud and slot connection 143 provides for limited changes in the amount of feeding movement of the feed wheel 127 thus providing for variations in spacing within limits. In accordance with the present invention, means is provided for obtaining spacings in excess of the spacing range thus afforded by the said stud and slot connection. In the embodiment of the invention herein shown and described, this is accomplished by utilizing the wire feed mechanism controlling means above described, including the treadle operated latch 56, the switch 58 arranged to be set one way or the other upon adjustment of the latch 56, and the described connections between the switch 58 and the wire feeding and wire cutting mechanisms, the illustrated embodiment of the invention comprising the provision of means whereby the control lever 52 may be swung one way or the other to adjust the latch 56 independently of the treadle and treadle rod 50.

To this end, the treadle rod 50 has a pin and slot connection 62, 64, with a rod 65, the upper end of which rod has a ball and socket connection 57 with the lever 52. A spring 66 seated in the bore in the rod 65 normally

tends to force the rod 50 downwardly and operates to restore the lever 52 to normal position after movement thereof against the pressure of the spring 66.

5 In the illustrated machine, as in the machine of said Letters Patent No. 490,621, the operating cam 40 for the wire feed mechanism, like the wire cutting mechanism cam 45, is a double throw cam so constructed 10 that during every revolution of the cam shaft 22 two operative movements of the wire feeding mechanism are effected. The present invention provides means for automatically and periodically swinging the lever 52 once in every revolution of the cam shaft 22 whenever said means is operative, thus throwing over the latch 56 and setting the switch 58 to suspend the operation of the wire feeding mechanism once in every 15 revolution of the cam shaft so that, when extra wide spacing is desired, every alternate wire feeding movement will be omitted automatically and, instead of feeding and inserting two fastenings during each revolution of the cam shaft, the machine will insert one fastening only during each revolution of the cam shaft.

20 Inasmuch as the described means for periodically suspending the operation of the wire feeding mechanism is independent of, and does not interfere with, the operation of the work feeding mechanism, it will be seen that, whenever the said means is operative, the work will have imparted to it two feeding 25 steps or movements between each two fastening inserting operations, thereby exactly doubling the spacing capacity of the machine.

20 As shown, the means for thus automatically and periodically swinging the lever 52 independently of the treadle rod 50 to effect alternate suspensions of the operation of the wire feeding mechanism comprises a double armed lever pivoted on the machine frame 45 on an extension of the shaft which carries the wire feed arm 31, which double armed lever carries on one arm 68 a roll 70 adapted to be engaged by an edge cam piece 72 fitted on the wire feed operating cam 40 and operating to swing the double armed lever once in every revolution of the cam shaft. The other arm 74 of the double armed lever is pivotally connected to one end of a rod or plunger 76, the other end of which rod is 55 arranged to be received in a recess 78 (Fig. 2) at one side of the lever 52. A spring 80 (Fig. 1) connected at one end to the machine frame and at the other end to the rod 76 acts both to force the rod 76 laterally in line with the recess 78 and also in the direction to maintain the roll 70 in contact with the edge piece 72 on the cam 40. Located in supports in the machine frame at one side of the rod 76 is a rotatable shaft indicated at 82 (Fig. 1) carrying a cam 84 so

located that rotating of the shaft 82 displaces the rod 76 laterally against its spring 80 out of line with the recess 78 so that, in the reciprocation of the rod 76 by engagement of the edge cam piece 72 with the roll 70 on the double armed lever, the rod 76 does not enter the recess 78.

70 The rotatable shaft 82 is designed to be provided with connections to a knee lever or treadle (not shown) by movement of which 75 the operator may rotate the said shaft at will during the operation of the machine to cause the lever 52 to be operated to move the latch 56 and set the switch 58 periodically once in every revolution of the cam shaft 22 80 to suspend the operation of the wire feeding mechanism.

85 In the use of the illustrated machine, the operator, in commencing operations upon a given piece of work, depresses the treadle which operates the treadle rod 50, thereby through the lever 52 and spring blade 54 positioning the latch 56 to set the switch 58 to render the wire feeding and cutting mechanisms and the horn raising and depressing mechanisms operative. If normal spacing is desired, the knee lever or treadle 90 controlling the periodic suspension of the wire feeding mechanism is set to position the shaft 82 so as to displace the rod 76 laterally out of line with the recess 78 in the lever 52.

95 Whenever extra wide spacing of the fastenings is desired, the operator moves the said knee lever or treadle oppositely to rotate the shaft 82 so that the rod 76 will 100 be positioned by its spring 80 in line with the recess 78 in the lever 52 whereupon, once in every revolution of the cam shaft 22, the lever 52 will be moved to set the latch 56 to operate the switch 58 in the direction to force the wedge shaped block 60 into operative relation to the rod 61, thereby forcing the cam roll 38 on the upward extension 36 of the wire feed lever 28 out of the path of movement of the cam 40 and, 110 at the same time, through the connections above described, rendering the wire cutting mechanism inoperative. So long as the rock shaft 82 and the rod 76 are so positioned, the wire feeding mechanism will operate 115 once only in every revolution of the cam shaft 22, and consequently only one wire feeding movement will be effected for every two work feeding movements.

120 It will be noted that the operation of the illustrated embodiment of the invention is entirely positive, with the result that maintenance of accurate time relationship of the parts of the control mechanism relatively to the other operating mechanisms of the 125 machine is assured.

130 Although the invention is herein shown and described as embodied in a machine of the type set forth in said Letters Patent No. 490,621, it is to be understood that the in-

vention is not intended to be limited to use in connection with machines of this type. Similarly, nothing herein is intended to limit the invention to use in connection with 5 a control mechanism of the type set forth in the above mentioned United States Letters Patent No. 383,455.

The novel feature of the illustrated mechanism whereby the feed of the wire may be 10 periodically suspended to increase the spacing between adjacent fastenings is more broadly claimed in the co-pending application of John Sayer, Serial No. 99,328, filed May 23, 1916, for fastening inserting 15 machines.

Having fully described our invention, we claim as new and desire to secure by United States Letters Patent:

1. In a fastening inserting machine, a 20 power driven shaft, fastening inserting means operated from said shaft, means for disconnecting said fastening inserting means from said shaft, a continuously operating device effective in one position thereof to 25 operate said disconnecting means periodically to render said fastening inserting means inoperative at predetermined times in the operation of the machine, and means for moving said device into and out of said 30 position.

2. In a fastening inserting machine, a power driven shaft, fastening inserting means operated from said shaft, means for disconnecting said fastening inserting means 35 from said shaft, a continuously reciprocating latch member effective in one position thereof to operate said disconnecting means to render said fastening inserting means inoperative, and means for moving said latch 40 member automatically into and out of said position periodically at predetermined times in the operation of the machine.

3. In a machine of the class described, a power driven shaft, wire feeding means operated from said shaft, means for suspending 45 the operation of said wire feeding means comprising a switch member and connections between the switch member and the wire feeding means, a latch member effective in one position thereof to operate the switch member in a direction to suspend the operation of the wire feeding means, and means for automatically moving said latch member into and out of said position periodically at regular intervals in the operation 50 of the machine.

4. In a machine of the class described, a power driven shaft, wire feeding means operated from said shaft, means for disconnecting 55 said wire feeding means from said shaft, a continuously reciprocating device effective in one position thereof to operate said disconnecting means, means operating automatically to move said device into and out of said position at regular intervals in

the operation of the machine, and means under the control of the operator for rendering said automatic means operative.

5. In a machine of the class described, wire feeding means, a power driven shaft, 70 operative connections between said means and said shaft, means for rendering said connections ineffective thereby suspending the operation of the wire feeding means, a device for operating said wire feed suspending means, means for automatically operating said device periodically at regular intervals in the operation of the machine to render said wire feed suspending means operative, and other means under the control of 75 the operator for operating said device independently of said automatic means to start and stop the operation of the wire feeding means.

6. In a machine of the class described, fastening inserting means, operating mechanism for said means, work feeding means operating in timed relation to the normal operation of the fastening inserting means, means for rendering said mechanism ineffective to operate said fastening inserting means without interfering with the operation of the work feeding means, a device movable relatively to said last-named means for controlling the operation of said last 85 named means effective in one position of said device to operate that means to render said mechanism ineffective, and means for automatically and periodically operating said device into and out of said position to 90 render said mechanism alternately ineffective and then effective thereby increasing the number of work feeding movements imparted to the work relatively to the number 95 of fastening inserting operations.

7. In a machine of the class described, wire feeding means, a stop device therefor, a switch to operate said stop device, a latch effective in one position thereof to move said switch device to render said stop operative, 110 and means under the control of the operator acting automatically and periodically when operative to move said latch into and out of said position at regular intervals in the operation of the machine.

8. In a fastening inserting machine, a power driven shaft, wire feeding means operated from said shaft, means for disconnecting said wire feeding means from said shaft, a device operative in one position 115 thereof to operate said wire feed disconnecting means to render the wire feeding means inoperative, and means for automatically moving said device into and out of said position, said last named means comprising a continuously operating member moving once in every revolution of said shaft in a direction to move said device into said position.

9. In a fastening inserting machine, a power driven shaft, wire feeding means op- 120

- 6
- erated from said shaft, means for disconnecting said wire feeding means from said shaft, a device operative in one position thereof to operate said wire feed disconnecting means to render the wire feeding means inoperative, means for automatically moving said device into and out of said position, said last named means comprising a continuously operating member moving once in 10 every revolution of said shaft in a direction to move said device into said position, and manual means for rendering said automatic means operative.
10. In a machine of the class described, a continuously rotating spindle, fastening inserting means operated from said spindle, means for disconnecting said fastening inserting means from said spindle, a device movable relatively to said last-named means effective in one position thereof to render said disconnecting means operative without interrupting the operation of said spindle, and means for automatically operating said device into and out of said position at regular intervals in the operation of the machine.
11. In a fastening inserting machine, a power driven shaft, wire feeding means operated from said shaft, means for periodically suspending the operation of said wire feeding means, manually operated means for starting and stopping the operation of said wire feeding means without affecting the continued operation of said shaft, and other manually operated means for rendering inoperative said wire feed suspension means.
12. In a fastening inserting machine, a power driven shaft, wire feeding means operated from said shaft, manually operated controlling means for said wire feeding means, automatic controlling means for said wire feeding means operated in timed relation with said shaft, and manually operated means for rendering said automatic controlling means inoperative.
13. In a fastening inserting machine, a power driven shaft, work feeding means, wire feeding means operated from said shaft for each operation of said work feeding means, means for suspending alternate operations of said wire feeding means without affecting the continued operation of said work feeding means, and manually operated means for rendering said wire feeding means inoperative during a plurality of 55 operations of the work feeding means constructed and arranged to disconnect said wire feeding means operatively from said wire feed suspension means.
14. In a fastening inserting machine, a power driven shaft, wire feeding means operated from said shaft, manually operated means for rendering said wire feeding means operative and inoperative during the operation of the machine, and means independent of said manually controlled means

for periodically suspending the operation of the machine when said manually controlled means is in operative position.

15. In a fastening inserting machine, a power driven shaft, wire feeding means operated from said shaft, controlling means for said wire feeding means, manually operated means for operating said controlling means into position to make said wire feeding means operative, and automatic means operated in timed relation to said shaft for moving said controlling means relatively to said manually controlled means into position to render said wire feeding means inoperative.

16. In a fastening inserting machine, a power driven shaft, wire feeding means operated from said shaft, controlling means for said wire feeding means, manually operated means for moving said controlling means into position to make said wire feeding means operative, a yielding connection between said controlling means and said manually operated means, and means for periodically moving said controlling means relatively to said manually operated means into position to render said wire feeding means inoperative.

17. In a fastening inserting machine, a power driven shaft, wire feeding means operated from said shaft, manually operated means tending normally in one position of said means to render said wire feeding means operative, and means operating in opposition to said means for periodically rendering said wire feeding means inoperative.

18. In a fastening inserting machine, a power driven shaft, wire feeding means operated from said shaft, controlling means for said wire feeding means movable from one position to another to render said wire feeding means operative or inoperative, manually operated means for moving said controlling means in either direction of movement so as to render said wire feeding means operative or inoperative, and other means for periodically moving said controlling means from operative to inoperative position.

19. In a fastening inserting machine, a power driven shaft, wire feeding means operated from said shaft, controlling means for said wire feeding means movable from one position to another to render said wire feeding means operative or inoperative, manually operated means for moving said controlling means in either direction of movement so as to render said wire feeding means operative or inoperative, and other means for periodically moving said controlling means from operative to inoperative position, said manually operated means comprising means for automatically moving said controlling means from inoperative to

operative position subsequently to the operation of said other means.

20. In a machine of the class described, wire feeding means, work feeding means, 5 and controlling mechanism for said wire feeding means comprising manually controlled mechanism operable to effect operation of said wire feeding means upon each 10 operation of the work-feeding means and to stop the operation of said wire feeding means without affecting the continued oper-

ation of said work feeding means and comprising automatically operated mechanism independent of said work feeding mechanism for suspending periodically the operation of said wire feeding means without affecting the operation of said work feeding means. 15

In testimony whereof we have signed our names to this specification.

ARTHUR ERNEST JERRAM.
JOSEPH GOULDBOURN.
